UNITED STATES PATENT OFFICE

LILIAN MAY BUTCHER, OF RHOS-ON-SEA, COLWYN BAY, NORTH WALES

HAIR NET

Application filed April 10, 1931, Serial No. 529,258, and in Great Britain December 19, 1930.

This invention relates to an improved hair net for use particularly in permanent hair waving, water setting and any other hair waving process.

5 It is the object of this invention to provide a hair net suitable for use in permanent hair waving and the invention consists in a hair net formed from a semi-rigid material such as a combination of wire and silk or like material.

Further features of the invention will be apparent from the following description.

In the accompanying drawings:—

Figures 1 and 2 are front and back views 15 respectively showing the hair net in position on the head of a person, and

Figure 3 is a fragmentary view of the hair net.

Referring to the drawings the improved 20 net *a* is formed of wire *b* (Figure 3) of a very fine gauge covered with silk thread or other suitable material *c*.

In the use of the improved net same is fitted on the head of a person over the previous 25 ly formed waves after same have been set for drying and due to the semi-rigid nature of the net same is found to hold the waves in position such that they cannot move from their set position without the necessity for holding 30 the net in position by hand as in the case of the nets hitherto employed for this purpose and which are made purely from silk or like fabric material.

An important advantage of the improved 35 net is that by the use of same it is possible to dispense with the usual pins for curling the ends of the hair since the semi-rigid net according to the invention serves itself to grip the ends of the hair and may be used to curl 40 same. It is also found that the hair is dried much quicker when the improved net is employed. The net may be formed around its peripheral edge with a number of extensions *d* and these may conveniently be used for the 45 purpose of curling the ends of the hair as above mentioned.

Having now described my invention, what I claim as new and desire to secure by Letters Patent is:

50 1. A hair net particularly intended for use

in permanent hair waving formed of pliable material capable of being shaped under the pressure of the fingers and of maintaining the shape imparted thereto whereby to hold the hair in a shape conforming to that of the net. 55

2. A net as claimed in claim 1, characterized in that the material thereof is constituted by a wire and a covering thereon.

3. A hair net as claimed in claim 1, characterized by the provision of extended portions 60 of the net adapted to curl the ends of the hair.

In testimony whereof I have signed my name to this specification.

LILIAN MAY BUTCHER.
